CLAIM

The ornamental design for a quilt cover, as shown and described.

DESCRIPTION

FIG. 1 is a front view of a quilt cover showing my new design;

FIG. 2 is a rear view thereof;

FIG. 3 is a left side view thereof;

FIG. 4 is a right side view thereof;

FIG. 5 is a front view of the quilt cover shown in a first alternate configuration;

FIG. 6 is a front view of the quilt cover in a second alternate position of use showing the article inside out; and,

FIG. 7 is an enlarged view of area 7 in FIG. 5.

The dot-dash broken lines represent boundaries of the enlarged portions and form no part of the claimed design.

1 Claim, 7 Drawing Sheets
